ARTICLE HOLDER

Anna V. Langhofer, Rock Island, Ill.

Application March 7, 1941, Serial No. 382,276

1 Claim. (Cl. 41—10)

This invention relates to article holders and more particularly to the provision of a holder of economical construction which will be highly efficient in use.

Another object of this invention is the provision in article holders of a novel ornamentation adapted to overlie the pocket formation provided in the holder.

A further object of the present invention is the provision of a novel pin-up pad holder which will be relatively simple to manufacture and effective for numerous uses.

Other objects and advantages residing in the present invention will appear more fully in the light of the following specification in view of the drawing in which

Fig. 1 is a front elevational view of my new article holder;

Fig. 2 is a vertical section through the same;

Fig. 3 is a fragmentary perspective detail of my new holder with a portion thereof folded back to disclose the pocket formation; and

Fig. 4 is a fragmentary perspective detail of the back side of my article holder showing the hanger means employed therein.

Referring to the drawing, the article holder is generally indicated at 10 and comprises a back member 11 formed of a fibre or paper dish having one-half of a like dish 12 disposed thereon with the concave portions of the two dishes facing each other. The segmental portion of the dish 12 is secured to the back member 11 by ornamental lacing or stitching 13 along the annular flanges 14 of the two dish elements 11 and 12.

The upper edge 15 of the segmental front wall 12 is disposed substantially in the plane of a horizontal axis struck across the back member 11 so that a substantial portion of the back plate 11 extends above the top edge 15 of the front member 12 thereby providing an opening 16 to a pocket formation 17 wherein there may be stored articles such as pads utilized in kitchens for grasping the handles of cooking utensils or fabric dish coverings commonly used to cover containers of food stuff in ice boxes.

The holder is completed by providing a closure member 18 consisting of a configuration depicting the head 19 of a doll which may be cut out of pasteboard. Attached to the lower edge of this member 19 is a skirting 20 of gingham cloth or the like which has the appearance of being a smock or other apparel worn by the doll. This assembly of the head and skirting is then sewed or otherwise fixed to the upper edge of the back member 11 along the flange portion 14 thereof so that the skirting 20 will flare out and overhang the opening 16 of the holder and be draped down over the front face of the holder.

The skirting 20 heretofore described provides a covering for the opening 16 of the holder pocket 17 to conceal the contents of the article holder as well as to provide a dust cap for the pocket.

5 The holder 10 may be suspended from a hook attached to the wall of the room wherein the holder is used and to this end there is provided a grommet element 21 which is fixed to the back plate 11 at the point where the head 19 and skirting 20 are sewed to the flange 14'. Or if desired, the back plate 11 may be mounted flush with the wall upon which it is to be mounted and any suitable means such as a tack, nail or screw fastened through the recessed wall 11' to support the holder on the wall.

From the foregoing description it is apparent that I have provided a novel article holder for use in kitchens and for other utility rooms and that I have provided a novel arrangement of 20 parts which will result in an article holder of a wide range of utility, and that such arrangement as I have herein disclosed provides a holder having sanitary features as well as neatness in appearance.

25 It is contemplated that such holders as herein described may be employed for numerous purposes other than those herein explained and for this reason I desire to avail myself of all the modifications and arrangements coming within 30 the scope of my invention.

While I have illustrated and described the preferred form of construction for carrying my invention into effect, this is capable of variation and modification without departing from the 35 spirit of the invention. I, therefore, do not wish to be limited to the precise details of construction set forth, but desire to avail myself of such variations and modifications as come within the scope of the appended claim.

40 Having thus described my invention, what I claim as new and desire to protect by Letters Patent is:

In a pin-up article holder comprising a relatively stiff circular fabric plate having a concave 45 form, a semicircular segment of a second relatively stiff fabric plate of a like form and arranged on said first-named plate with the edges thereof abutting the edges of the first-named 50 plate and with the concave portions of each plate exposed to each other in spaced relation with respect to each other, forming a non-collapsible pocket having an open upper end with a portion of said first-named plate extending a substantial 55 distance above the upper edge of the second-named plate, and means for securing the two plates in the aforesaid relationship with respect to each other.

ANNA V. LANGHOFER.
